THERMOSTATIC SAFETY CONTROL APPARATUS FOR GASEOUS FUEL BURNERS

Wilmer E. McCorquodale, Orange, Tex.

Application September 9, 1947, Serial No. 772,989

2 Claims. (Cl. 158—117.1)

1

This invention relates to gas burning apparatus in which a pilot light is utilized to light the main burner. The invention is more particularly directed to an improved arrangement for automatically shutting off the flow of gas not only to the main burner but also to the pilot burner in case the pilot light should become extinguished for any reason.

Numerous gas burning devices have been proposed for heating purposes, such as heating water or the like, wherein a pilot burner is provided to automatically light the main burner whenever gas is admitted thereto; and these devices generally include means for automatically shutting off the flow of gas to the main burner whenever the pilot light becomes extinguished, in order to prevent or minimize release of gas to the atmosphere with resultant hazard of explosion. Many of these devices, however, are so designed as to permit continued leakage of gas through the pilot burner even though the flow of gas to the main burner is shut off. While various arrangements have been proposed for stopping the gas flow to both the main burner and pilot burner, these generally have the disadvantage of being relatively complicated and expensive.

It is an object of this invention to provide a simple and inexpensive gas burning apparatus adapted to shut off the flow of gas to the main burner and pilot burner simultaneously whenever the pilot light becomes extinguished.

One specific embodiment of the invention is illustrated in the accompanying drawings in which:

Figure 1 is a plan view of the gas burning apparatus;

Figure 2 is a sectional elevation taken generally on the line 2—2 of Figure 1; and

Figure 3 is a more detailed view of the pilot shut-off valve taken on the line 3—3 of Figure 2 with a section of the valve broken away to show internal details.

Referring now to the drawings, the numeral 10 represents a main gas burner having a plurality of gas jets 11. Gas is supplied to the main burner through inlet line 12 which is screwed into the bottom of the burner. The inlet to the burner 10 includes a constricting portion 13 which provides a valve seat 14 adapted to cooperate with a valve plug 15 to shut off the gas from the main burner 10 whenever the valve plug is in contact with the valve seat as shown in Figure 2. Valve plug 15 is attached to valve stem 16 which extends upwardly above the burner 10

through a bushing 17 which is screwed into the top of the burner at its center. Bushing 17 is adapted to permit the valve stem 16 to slide up or down as the valve opens or shuts.

Burner 10 is provided with an upwardly projecting shoulder 18 which may be an integral part of the body of the main burner, as shown in the drawings. A bimetallic thermostatic element 19 is securely mounted on the shoulder 18 as by means of screw 20, and extends radially inward toward the center of the burner and is connected to the upper end of the valve stem 16 in any suitable manner. As shown in Figure 2, the thermostatic element proper may terminate short of the valve stem 16 and may be mechanically connected thereto by means of an extension arm 21 which is attached to thermostatic element 19 in any suitable manner. Extension arm 21 may be movably connected to the top of valve stem 16 by providing a grooved portion at the end of the arm to intermesh with a grooved portion of the valve stem as shown at 22.

A pilot burner 23 is mounted on main burner 10 directly beneath the bimetallic thermostatic element 19. If desired, a U-shaped shield 24 may be provided between the pilot burner and the thermostatic element to keep the pilot flame from coming into direct contact with the latter. Gas is supplied to the pilot burner 23 by means of a small gas supply line 25 having a valve 26 therein for shutting off the flow of gas. The gas line leading to pilot burner 23 also desirably includes a constricting portion, shown at 32, which restricts the rate of flow of gas therethrough to a small amount at all times.

Various known types of valves will function satisfactorily as the pilot gas valve 26 and any suitable type may be selected. The valve shown in Figure 3 is illustrative. This valve is designed to be in closed position when the valve plug and stem are in their lowermost position, as shown in Figure 3. A compression spring 33 tends to force the valve plug and stem downward and thus normally to keep the valve closed.

Valve 26 is mechanically connected to a movable portion of the thermostatic element 19 by means of a rod 27 having an arm portion 28 for connection with the valve by insertion through its handle portion 30. Rod 27 is threaded at its upper end for receiving adjusting nuts 29.

As illustrated in the drawings, both the main burner valve and the pilot gas valve are in closed position. In order to light the pilot burner, the handle portion 30 of the pilot gas valve may be manually pushed upwardly, thereby opening the

valve and admitting gas to pilot burner 23 which may then be lighted. Handle 39 should be held in its upward position until the pilot burner 23 has sufficiently heated thermostatic element 19 to maintain valve 26 open. As soon as the bimetallic thermostatic element 19 has become sufficiently hot from the heat of the pilot flame, thermostatic element 19 will flex upwardly, thus raising valve plug 15 and admitting gas to the main burner. The movable end of thermostatic element 19 will remain in its upward position until such time as the pilot light becomes extinguished. Whenever this happens, thermostatic element 19 will cool and thereupon flex downwardly to the lower position, thereby simultaneously closing the main burner valve and the pilot gas valve.

It will be apparent that numerous specific modifications may be made in the above described gas burning apparatus without departing from the scope of the invention. The invention is therefore not necessarily limited to specific details disclosed herein.

Having described my invention, what I claim and desire to protect by Letters Patent is:

1. A gas burning apparatus comprising a main gas burner including a hollow body member having a gas inlet located centrally thereof and adjacent its base, a valve seat at said inlet, a valve plug cooperative with said valve seat for shutting off the flow of gas to the burner when the valve is closed, a securing nut positioned on the upper portion of the body member directly above said valve seat, a valve stem extending from said valve plug through said securing nut and slidably mounted therein, a pilot burner positioned to light the main burner, a bimetallic thermostatic element above the pilot burner extending from adjacent the outer periphery of said body member radially inward and adapted to be heated by the pilot flame, one end of said thermostatic element being securely fixed adjacent said outer periphery and the other end being free to move vertically upon flexing of the thermostatic element, an extension arm directly connecting the movable end of said thermostatic element with the upper end of said valve stem

to close the valve and thereby shut off the flow of gas to the main burner upon extinguishment of the pilot light, means for supplying gas to said pilot burner, a valve operatively associated therewith for shutting off the gas flow and including resilient means constantly urging the valve toward closed position, said valve being disposed beneath a movable portion of said thermostatic element, and a vertically positioned rod extending from said last-named valve and connecting slidably with a movable portion of said thermostatic element, said rod being engageable with the thermostatic element when the latter is actuated upwardly, whereby said last-named valve is maintained in open position in opposition to said resilient urging means when the thermostatic element is flexed upwardly but closes simultaneously with the main burner valve whenever the pilot light becomes extinguished.

2. A gas burning apparatus according to claim 1 including means for varying the length of the connecting rod between the thermostatic element and the said last-named valve to permit adjustment for securing simultaneous closure of the valves.

WILMER E. McCORQUODALE.
